UNITED STATES PATENT OFFICE

162,988

COLLAPSIBLE BOTTLE CARRIER

William A. Ringler, Wayne, Pa., assignor to The Gardner-Richardson Company, Middletown, Ohio, a corporation of Ohio

Application May 7, 1949, Serial No. 2,513

Term of patent 14 years

(Cl. D58—5)

To all whom it may concern:

Be it known that I, William A. Ringler, a citizen of the United States of America, residing at Wayne, in the county of Delaware and State of Pennsylvania, have invented a new, original, and ornamental Design for a Collapsible Bottle Carrier, of which the following is a specification, reference being had to the accompanying drawings, forming a part hereof.

Referring to the figures:

Fig. 1 is a top plan view of a collapsible bottle carrier showing my new design,

Fig. 2 is a side elevational view,

Fig. 3 is a top perspective view thereof, and

Fig. 4 is a side perspective view thereof as it appears in collapsed position.

The essential features of my design reside in the portions shown in solid lines.

I claim:

The ornamental design for a collapsible bottle carrier, substantially as shown and described.

WILLIAM A. RINGLER.
